[57] CLAIM

The ornamental design for a fishing lure, as shown and described.

DESCRIPTION

FIG. 1 is a perspective view of the fishing lure, showing our new design;

FIG. 2 is a top elevation of the fishing lure;

FIG. 3 is a bottom elevation thereof;

FIG. 4 is a right side elevation thereof;

FIG. 5 is a left side elevation thereof;

FIG. 6 is a front elevation thereof; and,

FIG. 7 is a rear elevation of the fishing lure illustrated in FIGS. 1-6.

The broken line showing of a hook in FIGS. 4-7 for illustrative purposes only and forms no part of the claimed design.
